UNITED STATES PATENT OFFICE.

ALBERT M. FULLER, OF PITTSBURGH, PENNSYLVANIA.

AUTOMATICALLY-ADJUSTABLE GRINDING WHEEL.

Application filed February 27, 1922. Serial No. 539,421.

This invention relates to abrasive grinding machines, and particularly to means for compensating adjustment thereof to secure a constant positional relation of the grinding member to the stock being ground. More particularly the invention relates to machines employing a rotating abrasive grinding wheel, and the invention has for its object the provision of means to position the axis of the grinding wheel so as to keep the periphery thereof in constant relation to the stock, regardless of the wearing down of the periphery of the wheel caused by the grinding operation. Stated differently, the object of this invention is to provide automatic means by which the grinding wheel, after being set or adjusted to a desired position, is positively moved toward the stock being ground to continuously compensate for the radial reduction of the grinding wheel caused by wear.

The many uses and advantages of this mechanism will be apparent to those familiar with the art, from a reading of the following specification.

Referring to the drawings, Fig. 1 is a front elevation of a vertically arranged grinding apparatus embodying in a simple form the principle of this invention; Fig. 2 is a side elevation of the machine shown in Fig. 1; Fig. 3 is a horizontal section on the line III—III of Fig. 1; Fig. 4 is similar to Fig. 2, showing the relative position of the parts after the grinding wheel has been partly worn down; Fig. 5 is a side elevation showing a modification of the machine of Figs. 1 to 4, in that a lever arrangement is used instead of the pulleys of Fig. 1; Fig. 6 is similar to Fig. 5 except that the parts are shown in position as resulting from a material wearing down of the grinding wheel; Fig. 7 is a horizontal section on the line VII—VII of Fig. 5; Fig. 8 is another modification, showing a horizontally moving grinding wheel, in which the necessary adjusting force is provided by springs; Fig. 9 is a front elevation of the machine as shown in Fig. 6; Fig. 10 shows another modification, it being a side elevation of a horizontal machine, in which is embodied a correcting device to prevent inaccuracy due to wear other than that of the grinding wheel; Fig. 11 is a plan view of the machine shown in Fig. 10; Fig. 12 is a partial side elevation similar to Fig. 10, but with the parts in relative position resulting from

the wearing down of the grinding wheel and its follower; Fig. 13 is a vertical section on the line XIII—XIII of Fig. 10; Fig. 14 shows another modification, being a side elevation of a vertically arranged grinding mechanism embodying means for correcting inaccuracy due to wear other than that of the grinding wheel, the take-up acting through a system of levers; Fig. 15 is a partial front elevation of the machine of Fig. 14; Fig. 16 is a view similar to that of Fig. 14 with the parts in relative position resulting from the wearing down of the grinding wheel and its follower; Fig. 17 is a modification showing a vertically movable gravity type of grinder adapted to grind the inside of cylinders; Fig. 18 is an end elevation of the machine of Fig. 17; Fig. 19 is a partial plan view of the machine of Fig. 17; Fig. 20 is a modification comprising auxiliary springs, and a rotatable mounting for the entire grinding apparatus; Fig. 21 is a partial longitudinal vertical section through the machine of Fig. 20; Fig. 22 is a side elevation of a modification comprising a withdrawing lever; Fig. 23 is a side elevation of one of the levers used in the modification employing levers; Fig. 24 shows the grinder of Fig. 22 in withdrawn position; Fig. 25 shows the grinder of Fig. 22 after the grinding wheel has been worn down; Fig. 26 is a vertical section on line XXVI—XXVI of Fig. 25; Fig. 27 shows a modification in which the follower is not mounted to move in line with the grinding wheel; and Fig. 28 shows the mechanism of Fig. 27 after the grinding wheel has been worn down.

In grinding machines of this type as heretofore used the adjustment of the grinding wheel to compensate for the wearing away of its periphery has ordinarily been done by hand, at intervals, by means of a screw and hand-wheel, or other similar mechanism. Where the adjustment has been automatic it has also been intermittent. Manual means of adjustment has the disadvantage of giving only approximate accuracy in result, since the adjustment of the grinding wheel is necessarily intermittent, and dependent upon the personal judgment of the operator. Therefore the grinding is accurate only at the very time of adjustment, steadily becoming inaccurate as the grinder is used until it is adjusted again. In addition this method of adjustment requires a

considerable amount of a skilled mechanic's time, and the accuracy of the grinding depends entirely upon the skill, judgment and carefulness of the operator. Even if all of these factors are favorable there still remains the very serious objection that the adjustments being intermittent, necessarily result in variations of the grinding depth between adjustments. For example in grinding cylinders requiring accuracy within a limit of four one-thousandths of an inch, each inch of radial reduction of the grinding wheel would require five hundred separate adjustments to keep within the limit, and even with that number the cylinders turned out would necessarily vary as much as four one-thousandths of an inch at different diameters.

By the mechanism described in this specification a grinding wheel may be set or adjusted to a certain position, and thereafter it will be continuously and automatically moved towards the stock being ground as fast as the wearing off of the periphery of the grinding wheel reduces the radius thereof. The movement of the grinding wheel towards the stock being governed entirely by and coextensive with the reduction in radius of the grinding wheel, perfect accuracy in the depth of grinding may be constantly maintained. Since only one initial setting or adjustment of the grinding wheel is necessary, the invention is particularly applicable to quantity production, where many separate pieces are to be ground to exactly the same dimension, as for example where interchangeable parts are to be made by machinery, and where the fitting thereof must be very close and accurate.

Furthermore, in the grinding of certain tools, and parts of machinery or instruments, where accuracy to a thousandth of an inch, or less, is required, the adjusting means herein described will be found highly valuable, since the machine having once been set to secure the desired accuracy, requires no further adjustment until an entire grinding wheel has been worn out.

The principle upon which the invention is based comprises a circular rotatable grinding member so mounted that the axis of the wheel may move toward the stock to be ground, and a circular idler or follower slidably mounted so that its axis may move in a line directly towards the axis of the grinding wheel, the follower being made of any suitable wear resisting material, the peripheries of the two circular members being in contact, and the axis of the follower wheel being constantly urged directly towards the axis of the grinding wheel, and means connecting the movable bearings of the follower and grinding wheel to a fixed member in such manner that the movement

of the grinding wheel towards the stock is constantly limited to a distance exactly equal to the radial reduction of the grinding wheel by wear.

This principle may be applied in a great many different forms of machines, and the grinding mechanism may be variously mounted and arranged, to operate vertically, horizontally, or at any desired angle, as will be apparent from the following examples, which are to be understood as illustrative only, the invention being adapted to various changes and modifications of mechanism to meet special cases.

The illustrations show grinding wheels having a straight grinding edge parallel to the axis of the wheel, but it is to be understood that the grinding face or edge of the grinding wheel may be of any contour that may be required for grinding the stock to any particular shape.

In Figs. 1 to 4, there is illustrated a very simple form of gravity actuated grinding mechanism embodying this invention. This comprises a rigid base 1 from which extends a vertical V-shaped frame member 2 carrying at its top a rigid extension 3 in which is supported a screw 4, carried by a nut 5, which seats on the top of the arm 3. Rotation of the nut 5 raises or lowers the screw, which may be locked in adjusted position by means of a bolt 6 engaging a groove or key-way 7 in the screw 4. The lower end of the screw 4 is in the form of a fork 8 through which extends a pin 9, supporting a balanced cross member 10, to the ends of which are attached flexible cables 11. These cables extend around pulleys 12 rotatably mounted upon pins 13 fixed in the sides of a slidable block 14. This block engages a T-headed extension 15 from the vertical frame member 2, as more clearly illustrated in Fig. 3. The cables 11 extend around the pulleys 12, and their other ends 16 engage pins 17 fixed in a slidable block 18 which is mounted on a T-head 19 extending from the outer face of the block 14.

Fixed to the lower end of the block 14 is a motor M having a horizontal shaft A upon the projecting end of which is mounted a grinding wheel G.

Upon the block 18 by any suitable form of bearing, as for example the two-piece bearing formed by the cover plate 20, there is mounted a second horizontal shaft B, the projecting end of which carries fixed thereon a follower wheel, or follower F. This follower is preferably made of a resistant material such as steel, or fibre, raw hide, or the like, so that it will not be readily worn. The grinder G and the follower F are so positioned upon their respective shafts that their peripheries are adapted to form a tangential contact as illustrated. The slidable mounting of the block 14, which supports the

grinder G, and of the slidable block 18, which supports the shaft B, is such that the shafts A and B may move to and from each other on their line of centers.

5 The block 14 is mounted so that it is free to slide up and down with reference to the rigid T-head extension 15 of the frame 2, and the block 18 is mounted so that it is free to move up and down with reference 10 to the T-head extension 19 of the block 14. The cables 11 are fixed at one end to the cross-head 10, and after passing around the pulleys 12 are fixed to the pins 17 at their ends. These cables 11 therefore support 15 the block 14, which carries the motor M and grinder G. The ends 16 of the cables being attached to the pins 17, fixed in the block 18, can only move downward as the block 18 moves downward. But the downward 20 travel of this block 18 is limited by contact of the periphery of the follower F, which bears upon the periphery of the grinder G. That is to say, the relative movement towards each other of the shafts A and B 25 is limited by the sum of the radii of the grinder G and follower F. As long as this distance remains the same the follower F cannot move downward, the portion of the supporting cables between the pulleys 12 30 and the pins 17 remains constant, and consequently the entire apparatus mounted on the block 14 is suspended at a point determined by the length of cables between the support 10 and pulleys 12. The length of this portion of the cables can only be increased by 35 the lowering of the pins 17, and these can only be lowered by reduction of the distance between centers of the shafts A and B.

As the periphery of the grinding wheel G 40 wears off the follower F moves down a vertical distance equivalent to the radial reduction of the grinding wheel. This in turn permits the lowering of the pulleys 12, and consequently of the grinder G.

45 The result will be that as the grinding wheel is worn off radially the follower F will move down a distance equal to twice the radial reduction of the grinding wheel, and the grinding wheel itself will move 50 downward a distance equal to its radial reduction. Consequently the effective peripheral grinding contact of the grinding wheel will always be maintained at exactly the same height with respect to the stock S 55 which is being ground, and the machine grinds to the same depth, continually adjusting itself by lowering of the carrying mechanism as fast as the grinding wheel wears off.

60 It will be noted that when the mechanism is adjusted for operation, the cross-head 10 to which the cables are attached, becomes a fixed member in relation to the grinding contact of the periphery of the grinding wheel with the stock to be ground. A fixed

member in some form is an essential component of the mechanism in any of the various modifications in which the principle of the invention may be applied.

By loosening the screw 6 and turning the nut 5, the screw 4 may be raised or lowered as desired, and consequently the grinding mechanism may be set to cut at any desired distance from the upper surface of the table T. By this means the machine may be set 70 to grind at any desired thickness. If stock of varying thickness be fed under the grinder, it is possible that in case of unusual thicknesses the entire grinding mechanism may be lifted and so not secure a 75 grinding to the required depth. In such case the stock would have to be run enough times under the grinder to reduce it to the desired thickness. But in no case can the grinder cut to a greater depth than that to 80 which it has been adjusted, since it is positively locked by the mechanism above described so that the grinding wheel cannot go lower than its adjusted position. Its axis will move down as fast as its periphery 85 wears off in radial measure, and not otherwise.

In such cases if the weight of the grinding mechanism is heavier than the desired pressure of the grinding wheel upon the stock, a counterweight may be used to lift part of the weight of the mechanism. By 90 this means the pressure of the grinding wheel upon the stock may be adjusted as required.

100 In the illustrations given in Figures 1, 2, 3 and 4 the axis of the follower moves toward the axis of the grinding wheel in the line of movement of the grinding wheel axis toward the stock to be ground. The axis of 105 the follower may, however, move toward the axis of the grinding wheel in any direction, as the effect in any case is to lengthen the controlling cable between the pulley 12 and the cross-head 10 an amount equal to the 110 distance the axis of the follower moves toward the axis of the grinding wheel, this distance being always limited to and co-extensive with the radial reduction of the grinding wheel. The controlling cable between 115 the pulley 12 and the cross-head 10 must be parallel to the line of movement of the axis of the grinding wheel toward the stock to insure accurate adjustment.

120 Referring to Figs. 5, 6 and 7 a machine is illustrated, in which a lever is employed in place of a pulley arrangement as in Fig. 2, for securing the relative movement of the parts. The machine illustrated in these figures comprises a rigid vertical supporting frame 25, having a rear extension 26, in which is mounted an adjustable screw 27 having an operating nut 28 and a locking bolt 29. The upper portion of this screw is 125 formed into a fork 30 through which extends 130

4

a pin 31, which carries a cross arm 32 to the outer ends of which are pivotally attached by means of screws 33 the ends 34 of levers 35, which carry at their middle point laterally 5 projecting cylindrical studs 36, upon which are carried horizontal extensions 37 of vertical supporting members 38, which carry at their lower ends the slidable block 39 upon which is mounted shaft A⁵ of the grinder G⁵.

10 A similar block 40 is likewise mounted on the frame 25, and is vertically slidable thereon, by means of a T-head connection, as illustrated in Fig. 7. This block 40 carries in suitable bearings the shaft B⁵ on which is mounted an idler or follower F⁵. The grinder and follower are in peripheral contact as illustrated in Figs. 5, 6, and 9, and the movement towards each other of the shafts A⁵ and B⁵ is limited by the sum of 15 the radii of the wheels G⁵ and F⁵, as will be obvious. The arms 38 which support the block 39 upon which is mounted the grinding wheel are limited in their downward movement by the studs 36, at the middle points 20 of the levers 35. The free ends 41 of these levers bear upon the top of the block 40, or extensions 42 thereof, and these ends are free to slide horizontally on these extensions.

25 By this arrangement when the radius of the grinding wheel is reduced by abrasion 30 the follower F⁵ moves downward, keeping in contact with the grinding wheel. This lowers the free end 41 of lever 35, which bears upon the slidable supporting block of the 35 said follower. This lowers the middle point of the lever, that is to say the pin 36, which in turn permits the lowering of the carrying arms 38 and consequently the block 39. The 40 grinding wheel will be lowered a distance exactly equal to the reduction of its radius, while the follower will be lowered a distance exactly twice the reduction in radius of the 45 grinding wheel. Primary adjustment is made by means of the screw 27, and thereafter the horizontal level of the grinding point of wheel G⁵ is constantly maintained regardless of wear of the periphery. Fig. 5 shows the machine as preliminarily adjusted, with a full sized grinding wheel, and Fig. 6 50 shows the parts in relative position after the grinding wheel has been worn down.

In Fig. 8 there is illustrated a modification of the arrangement shown in Figs. 5, 6 and 9, in that the grinding wheel G⁸ and follower F⁸ are mounted in a horizontal frame, and are urged toward the stock to be ground by tension of a spring or springs 50. One end of this spring is fastened to an extension 51 from an adjustable screw 52, mounted in an 60 extension 53, from the fixed frame of the machine. The other end of the spring is attached to an extension 54 from the slidable block member 55, upon which is mounted the shaft B⁸, carrying the follower F⁸. The 65 grinding wheel G⁸ is mounted on shaft A⁸ in

a similar block 56, likewise slidably mounted in the main frame so that it can move towards the stock S⁸, being ground.

A screw 57 extends through an extension 58 from the main frame, and is controlled 70 by a nut 59, and locked in adjusted position by means of set screw 60, as will be obvious. A fork 61 of the screw 57 carries a cross member 62, to the ends of which are attached the ends 63 of levers 64, at the middle points of which are studs 65. The free ends 66 of the levers bear upon the rear side of extension 67 from the block 55. Cross extensions 68 of connecting members 69 engage cylindrical pins or studs 65, and 75 the other ends of the members 69 are secured to the block 56 which carries the shaft A⁸ of the grinding wheel. Consequently the tension spring 50 constantly urges the follower F⁸ against the periphery of the grinding wheel G⁸, and consequently urges the grinding wheel toward the stock being ground. As fast as the grinding wheel wears off the follower moves toward the center of the grinding wheel, which permits the 80 end 66 of the lever 64 to move towards the grinding wheel, and this in turn permits the grinding wheel to move toward the stock a distance equal to one-half the movement of 85 the follower, as will be obvious. Consequently, by this arrangement, acting on the same principle as those described above, the grinding wheel is maintained at a constant position with reference to the stock being ground.

90 Referring to Figs. 10, 11, 12 and 13 a further modification is shown in that a second follower, is provided to compensate for any wear that may occur in the follower in contact with the grinding wheel. The machine 95 illustrated in these figures is of the horizontal type, the grinding wheel G¹⁰, follower F¹⁰, and the auxiliary follower f¹⁰ being mounted upon slidable blocks 70, 71, and 72 respectively carried by T-head member 73 100 slidably mounted on the top of the machine frame 92. The follower f¹⁰ is constantly urged towards the left, that is towards the grinding wheel by means of a weight W, carried on the end of a cable 74, 110 which runs over a pulley 75 carried in the side of the movable frame member 91, the other end being attached to the slid- 115 able block 72. The periphery of the follower f¹⁰, bears against the periphery of the follower F¹⁰, which in turn bears against the periphery of the grinder G¹⁰, and consequently the pressure produced by the weight W tends constantly to keep 120 the three wheels pressed together and tends to move them in their common line of centers toward the grinding point.

A horizontal bar 76 is mounted in an extension from the block 72 in which is housed the shaft C¹⁰ of the follower f¹⁰, and this 125

bar is threaded so that its position may be adjusted by means of the locking nuts 77, as will be obvious. The other end of the bar passes loosely through a guide member 78, 5 and terminates in a fork 79, which carries a pivotally mounted cross member 80, to the ends of which are attached cables 81. These run around pulleys 82, carried on the side of block 71, and then around pulleys 83 10 mounted on the slideable block 70, the other ends being fixed to lugs 84, extending from the movable frame member 91.

By this arrangement the travel of the grinding wheel towards the stock is limited 15 by the cables 81, one end of which is attached to a fixed point of the frame, the other end of which is attached to the cross member 80. As the periphery of the grinding wheel G^{10} wears down the follower F^{10} 20 moves an equal distance toward the center of the grinding wheel. This permits the forward travel of the center of the grinding wheel a distance equal to the reduction in radius caused by the wearing off. The 25 follower f^{10} advances with follower F^{10} , and consequently the effect so far as the cable 81 is concerned is exactly as if it were rigidly attached to the pulley 82 or block 71.

But should the follower F^{10} itself wear off 30 from contact with the grinding wheel, and so become reduced in diameter, as indicated in Fig. 12, the secondary follower f^{10} will in that case move forward with relation to the first follower, maintaining a constant 35 contact. This will result in the advance of the connecting rod 76 relative to the center of the follower F^{10} a distance equal to the reduction in radius of follower F^{10} , and therefore will lengthen that portion of the 40 cables between the cross member 80 and the pulleys 82 an equal amount. The result will be to exactly compensate in so far as the length of cable between the pulleys 82 and 83 is concerned for the reduction in diameter of 45 the follower F^{10} .

In connection with this form of machine is shown a screw 85, having a hand-wheel 86, and a micrometer adjusting scale 87, 5 with a locking bolt 88. The screw is rotatably mounted in an extension 89 from the main frame, and its threads engage an extension 90 from a sliding auxiliary base 91, mounted on T-head 92 of the main frame. This arrangement also furnishes a means of 55 accurate adjustment of the grinding depth, as will be obvious.

Fig. 12 shows the relative position of the parts after the grinding wheel and the first follower have been worn down from their 60 original conditions as indicated in dotted lines.

In Figs. 14, 15 and 16 there is illustrated another modification of the machine, comprising a vertically movable grinder, with a 65 secondary compensating follower, the vari-

ous rotatable members being connected by a system of levers. This machine has an adjusting screw 100, with a micrometer scale 101, the lower end of the screw being mounted upon an extension 102 from the fixed 70 base, and the upper end mounted in an extension 103 of the same base, an intermediate sleeve member 104 being mounted on the screw and adapted to be moved up and down by rotation of the threaded scale member 75 101. An extension 105 from the member 104 engages an extension 106 from an auxiliary slideable frame 107 which carries the operating part of this particular grinder and is mounted on a T-head 99 carried by base 98. 80 Slidably mounted on the T-head of frame member 107 is a block 108 carrying the shaft A^{14} , which in turn carries the grinder G^{14} . A similar block 109 is likewise mounted on the frame 107, and it carries the shaft B^{14} 85 upon which is mounted the primary follower F^{14} , the periphery of which is in contact with that of the grinder as previously described in connection with the other figures. The auxiliary follower f^{14} is mounted on a 90 slideable block 110, which carries the shaft C^{14} . Adjustable weights W^{14} may be mounted upon the block 110 in order to give it sufficient weight. Thus the three blocks 108, 109 and 110 are urged in the same line by 95 gravity towards the stock S beneath the grinding wheel. The block 108 is supported by vertical members 111, attached to the block at their lower ends, and having lateral horizontal extensions 112 at their upper 100 ends. These extensions pass over, and rest upon semi-cylindrical pins 113, positioned at the middle points of levers 114, which are pivotally mounted at one end by pins 115 to the sub-frame 107, the other ends 116 of the levers bearing upon the upper ends of slideable block members 117, which at their lower ends rest upon the upper faces of the outer ends 118 of levers 119, which at their 105 middle points are pivotally mounted by pins 120, carried by extensions from the block 109. The other ends 121 of the levers 119 support the bottoms of vertical members 122 which at their upper ends are rigidly attached to the block 110. The free ends of 115 all levers are circular, in this and the other figures.

By this arrangement of parts as the grinding wheel G^{14} wears off the follower F^{14} 120 moves down sufficiently to take up the reduction in radius, and this permits the lowering of the center of the grinding wheel a distance equal to the reduction in radius thereof. This follows from the arrangement of the lever 114, the supporting of the main grinding wheel from the middle thereof, and the bearing of the free circular end of the lever upon the carriage of the follower F^{14} . Any wear that occurs in the follower F^{14} 125 itself is compensated for by the arrange- 130

ment of the auxiliary follower F^{14} , which is supported by the members 122, resting upon one end of the levers 119, pivoted at their middle points to the supporting carriage of the follower F^{14} . In case of any reduction in the radius of the primary follower F^{14} , the secondary follower F^{14} moves downward sufficiently to take up the loss. This forces downward the end of the levers 119 upon which the supports 122 rest, and consequently the outer ends 118 of these levers are raised an equal amount, which, being transmitted through the blocks 117 raise the ends 116 of the levers 114, and consequently neutralize the effect of reduction in size of the follower F^{14} in so far as it governs the lowering of the grinding wheel G^{14} .

The various parts are shown in position in Fig. 14 and their relative movement caused by a reduction of the grinding wheel and primary follower is shown in Fig. 16.

In Figs. 17, 18 and 19 a modification is shown applying the principle of this invention to a grinder adapted for use on the inside of a hollow cylinder which is moved around the grinder. This comprises a base 130 having two vertical uprights 131, with a cross-head 132, the inner sides of the vertical frame having guides 133, in which is slidably mounted a block 134 which carries this particular form of grinder. An adjustable screw 135 is carried by an extension 136 from the cross-head 132, and the screw may be locked in position by the bolt 137. Suspended from the lower end of the screw 135 by a hook 138 is a cable 139 which passes around a pulley 140 mounted between extensions 141 from the block 134. The cable passes through an opening in the block, and around a second pulley 142 mounted on a vertical extension 143 from a horizontal housing member 144 through which extends the shaft A^{17} carrying at its outer end the grinding wheel G^{17} , and having at its other end a pulley 145 adapted to be driven by a belt.

Pivotedly mounted by pin 150 in extension 151 from the main block 134 is a laterally extending shaft 152, on the outer end of which is carried a follower F^{17} . Suitable weights W^{17} may be mounted upon a vertically movable member 155, the lower end of which bears against the top of the block 134, and constantly urges it downward. It will be understood that the housing 144 is rigidly connected to the block 134, which is held in constant vertical position by means of the guides 133 of the main frame. Consequently the shaft A^{17} is positively maintained in horizontal position. The block 134 is suspended and positioned vertically in the guideway by means of the cable 139. As the grinding wheel G^{17} wears away the follower F^{17} moves downward. That loosens the cable 139, permitting the entire block

134, and the grinding mechanism carried thereby to move downward a corresponding distance, as will be obvious.

But since the follower F^{17} is mounted at the end of the shaft 152, which moves about the pin 150 as a center, there is a slight difference between the downward travel of the follower F^{17} , moving in an arc, and the amount of slack supplied to the cable 139 by this movement of the follower. This difference is compensated for by making the face of the follower F^{17} slightly curved toward its outer edge, as illustrated, so that as the grinding wheel is lowered, the point of contact of the follower and grinder will shift toward the outer edge of the follower, and the cable will be lowered a distance equal to the actual reduction in radius caused by wearing off of the grinding wheel G^{17} . If space permits, this type of machine may be made with sliding bearings for the follower, thus securing exact adjustment without modification of the face of the follower.

The particular arrangement would not be entirely accurate, without the curved surface of the follower F^{17} , but by the compensating means above described, and by making the carrying shaft 152 of a considerable length, the results obtained will be substantially constant, and at any rate sufficiently accurate for ordinary cylinder grinding.

In Figs. 20 and 21 a modification is shown in that instead of depending upon gravity to secure the lowering of the grinding wheel, the block 134^a is urged relative to the guides 133^a by means of coil tension springs 160, one end of which is fastened to the block 134^a and the other end of which is attached to the main frame, or to the guides 133^a. The principle of operation, so far as this invention is concerned is the same, but the grinding apparatus of Figs. 20 and 21 may be operated in any desired position, as for example by grinding underneath a part, the grinding wheel being above the follower, or by rotating the entire grinding apparatus inside of a cylinder which is being ground.

In Fig. 17 the cylinder 161 must be slowly rotated about the grinding wheel as the grinding progresses, in order to bring the stock surface to be ground into contact with the grinder.

The controlling members of the mechanism may be mounted in a wide variety of forms. For example, Fig. 22 is a side elevation of an arrangement wherein the straight controlling lever 162 is pivoted at its middle point by the pin 163 on the slidable block 175 on which is mounted the motor M^{22} carrying on one end of its shaft A^{22} the grinding wheel G^{22} . The follower F^{22} is mounted on a block 173 which is slidably mounted on T-head extension 176 of the block 175. The entire grinding and automatic adjusting mechanism is mounted upon

the auxiliary frame 164 which is slidably mounted to move toward and from the stock upon the main frame 168. A hand lever 165 is pivoted at its lower end on the main frame 168 by a pin 167 and is connected with the auxiliary sliding frame 164 by a link 166. One end of lever 162 bears against a vertically faced extension 171 of the auxiliary frame 164 and when the mechanism is adjusted for operation this extension 171 becomes the fixed member with relation to control of movement of the grinding wheel. The upper end of the lever 162 bears upon a vertically faced extension 172 from the 5 slidable block 173 upon which the follower F²² is mounted. Cylindrical bearing lugs at the ends of the lever 162 extend laterally to engage the extensions 171 and 172, their centers being on the center line of the lever 162. These circular bearings insure accurate 10 adjustment at all positions taken by the lever 162 as the grinding wheel wears away. The bearing face of the extension 171 is at a right angle to the line of movement of 15 the axis of the grinding wheel G²² and the bearing face of the extension 172 is at a right angle to the line of movement of the axis of the follower F²². The movement of 20 the grinding mechanism is actuated by a weight W²² attached to the lower end of a cable 177 passing over a pulley 179 pivoted on a lug extending from the main frame 168, the other end of the cable being attached to a rigid arm 174 extending from the 25 slidable block 175.

As the grinding wheel G²² wears away, the upper end of the lever 162 in contact with the extension 172 moves toward the grinding wheel G²² a distance equal to the 30 radial reduction of the latter. The lower end of the lever 162 in contact with the extension 171 moves an equal distance in the opposite direction with relation to the block 175, permitting the latter to move an equal 35 distance toward the stock. The axis of the grinding wheel G²², which is mounted on the block 175, is therefore constantly moved toward the line of grinding contact a distance exactly equal to the radial reduction 40 of the grinding wheel by wear.

The extension 171 carries a removable gauge or stop 170 which is adapted to form an abutment for the adjustable stop 169. The adjustable stop being once set, the 45 entire grinding mechanism may be withdrawn from the stock by pulling the hand lever 165. On releasing the hand lever 165 the auxiliary frame 164 returns to its former position and the line of grinding contact on the 50 periphery of the grinding wheel is in exactly the same position as before. Thus the stock may be changed without necessitating any re-adjustment of the grinding mechanism. This arrangement is valuable if the 55 stock has several sections to be ground to

the same measurement and it is necessary to withdraw the grinding wheel to reach the different sections, as, for example, the bearings of an automobile crank shaft, the teeth of a circular saw, etc.

70

If the stock is to be ground to different dimensions, several removable gauges or stops 170 may be used corresponding to the different dimensions and after once setting the grinding mechanism the articles may be 75 ground in duplicate by inserting the appropriate gauges or stops 170 for the different sections.

It is obvious that instead of moving the auxiliary frame 164 by means of the hand lever 165, this movement may be controlled by suitable jigs or patterns acting automatically. By controlling the movement of the auxiliary frame 164 by means of a mechanism, constructed on the principle of the 80 Blanchard lathe, irregular forms may be ground in duplicate for quantity production without necessitating any adjustment of the grinding mechanism other than the initial 85 setting.

Fig. 23 is a side view of the controlling lever 162 showing the circular lateral extensions 178 which engage the bearing faces 90 of the extensions 171 and 172.

Fig. 24 shows the same arrangement as Fig. 22 but with the grinding mechanism withdrawn and held away from the stock by the pawl 179 engaging the ratchet at the lower end of the hand lever 165.

Fig. 25 shows the same mechanism as Fig. 22 but with the members in their relative positions after the grinding wheel G²⁵ has been considerably reduced by wear, the original size being indicated by a dotted line. It will be seen that the grinding contact of the 100 periphery of the grinding wheel is in the same position with relation to the fixed member 171 as is shown in Fig. 22 before the 105 diameter of the grinding wheel has been reduced by wear.

Fig. 26 is a sectional view of the mechanism on the line XXVI—XXVI of Fig. 25, showing the construction of the sliding members, also the relative position of the arms 174^a to which the cable carrying the actuating weight is attached, and the lugs 181 on which the pulleys are pivoted.

Fig. 27 shows diagrammatically an arrangement of the members in which the axis of the follower F²⁷ moves toward the axis of the grinding wheel in a line at an angle to the line from the axis of the grinding wheel to the point of grinding contact 182. The grinding wheel G²⁷ is mounted on a 115 slideable frame 183 which is movable toward and from the stock S²⁷ to be ground, permitting the axis of the grinding wheel to move toward the grinding contact. The follower F²⁷ is mounted on a slideable block 184 having an extension 185 the bearing face of 120 125 130

which is at a right angle to the line connecting the axes of the grinding wheel and follower. The block 184 slides upon a T-head extension 186 of the slideable frame 183 5 toward the grinding wheel G²⁷ as the latter wears away. The controlling lever 187, instead of being straight as in the previous illustrations, is composed of two equal arms the central lines of which extend at an angle 10 from its pivotal center, the center of the pin 188 by which the lever is pivoted on the slideable frame 183.

At whatever point on the periphery of the 15 grinding wheel the contact with the follower 187 may be arranged, the angle Z of the central lines of the arms of the lever 187 extending from its pivotal point 188 is always equal to the angle Y of the lines extending from the axis of the grinding wheel to the 20 axis of the follower and to the point of grinding contact 182. The circular bearing at the end of the upper arm of the lever 187 engages the straight bearing face of the extension 185 and the circular bearing at the 25 end of the lower arm engages the straight bearing face of the fixed member 189 which extends at a right angle to the line from the axis of the grinding wheel to the point of grinding contact 182.

30 As the grinding wheel G²⁷ wears away the block 184 and the bearing face on the extension 185 move toward the grinding wheel G²⁷ a distance equal to the radial reduction of the latter. The bearing on the 35 upper end of the lever 187, being constantly in contact with the bearing face of the extension 185, moves an equal distance. If the frame 183 were stationary, the bearing of the lower end of the lever 187 would move 40 away from the grinding wheel an equal distance, but since the frame 183, to which the lever is pivoted, is constantly urged toward the stock by the weight W²⁷, the bearing on the lower end of the lever is constantly held 45 against the bearing face of the fixed member 189, so that the pivotal point 188 of the lever and the frame 183 carrying the grinding wheel G²⁷ are constantly moved toward the stock a distance exactly equal 50 to the radial reduction of the grinding wheel by wear.

Fig. 28 shows the same mechanism as Fig. 27, but with the members in their relative positions after the grinding wheel G²⁸ 55 has been considerably reduced by wear, the original size being indicated by a dotted line. It will be seen that the point of grinding contact on the periphery of the grinding wheel is in the same position with relation to the fixed member 189 as is shown in Fig. 27 before the diameter of the grinding wheel has been reduced by wear.

60 It will be understood that the embodiments above described are illustrative only, and that many variations in structure, and

many adaptations of the general principle may be devised. I do not desire to be limited to the specific forms shown, and have not tried to illustrate all possible or desirable forms, but believe that those shown are sufficient to inform anyone skilled in the art how to practice the invention in a variety of other forms.

70 I claim:

1. A grinding mechanism comprising a 75 circular rotary abrasive member, a circular non-abrasive rotary follower member, having a common plane of rotation with the abrasive member and contacting tangentially at its periphery with the periphery of the 80 abrasive member, the abrasive member being constantly urged towards the stock being ground and the follower towards the axis of the abrasive member, and a connection between the abrasive member and the 85 follower member whereby travel of the abrasive member toward the stock is governed by travel of the follower toward the abrasive member.

2. A grinding mechanism comprising a 90 rotary abrasive member, a rotary follower member positioned in the plane of rotation of the abrasive member and contacting at its periphery with the periphery of the abrasive member, and a positive connection 95 between the said abrasive and follower members whereby movement of the abrasive member toward the stock to be ground is limited by movement of the follower toward the axis of the abrasive member.

100 3. A grinding mechanism comprising a rotary abrasive member, a rotary follower member positioned in the same plane as and in tangential peripheral contact with the abrasive member, a movable support for the 105 abrasive member adapted to permit it to move toward the stock to be ground, a movable support for the follower member adapted to permit it to move toward the axis of the abrasive member, the abrasive member being constantly urged toward the stock and the follower member constantly urged toward the axis of the abrasive member, and a connecting member between the abrasive member and the follower whereby movement 110 of the abrasive member toward the stock being controlled by movement of the follower toward the axis of the abrasive member.

115 4. An abrading machine comprising a 120 rotary grinding wheel, a support for the grinding wheel movable toward the stock being ground, a follower wheel contacting peripherally and tangentially with the grinding wheel, a slideable support for the 125 follower, and a positioning member carrying the support for the grinding wheel at an intermediate point, one end of said positioning member being limited in movement toward the stock by a fixed member and the 130

other end limited by movement of the support of the follower, whereby the movement of the grinding wheel support is determined by movement of the follower support.

5. In a grinding machine, the combination of a rotary abrading wheel, a mounting therefor movable toward and from the stock to be ground, a follower wheel adapted to contact tangentially at its periphery with the periphery of the abrading wheel, a movable mounting therefor, the follower being constantly urged toward the axis of the abrading wheel and the latter toward the stock, and connections between the mounting of the follower and the mounting of the abrading wheel and a fixed member whereby to limit movement of the abrading wheel toward the stock to a distance equal to the radial reduction of the abrading wheel.

10. In a grinding machine, the combination of a stationary stock-holding element, a rotatable circular abrading member having a carriage mounted to slide toward and away from the stock-holding element, a circular rotatable follower having its periphery in tangential contact with the periphery of the abrading member, a slideable carriage for the follower, and means positively connecting the two slideable mountings with each other and with a fixed member whereby movement of the abrading member toward the stock-holding element is controlled by movement of the follower toward the axis of the abrading element.

35. 7. In a grinding machine, the combination of a work-supporting element, a rotatable abrading element having a circular abrading face, one of said elements being mounted for movement toward and from the other, a rotatable follower bearing tangentially against and continuously urged toward the abrading face of said abrading element, and means controlled by the position of the axis of said follower with relation to the axis of the grinding element for moving said movable element toward the other element in proportion to the diminution in the radius of the grinding element whereby the work-supporting element is continuously maintained at a fixed position with relation to the face of the abrading element.

8. In a grinding machine, the combination of a rotary abrading grinder, a carriage therefor mounted to slide to and from the stock to be ground, a rotary follower adapted to contact at its periphery with the periphery tangentially of the grinder, a carriage for the follower slideably mounted so that the axis of the follower is movable towards the axis of the grinder, means urging the follower towards the grinder and the grinder towards the stock, and a controlling member having one end limited in movement by a fixed member and the other

end limited in movement by the carriage of the follower, forward movement of the carriage of the grinder being governed by movement of an intermediate point of said controlling member, whereby as the follower moves towards the axis of the grinder the latter is permitted to move an equal distance towards the stock.

9. An abrading machine comprising a rotary grinder slidably mounted to move toward and from the stock being ground, a rotary follower adapted to contact tangentially at its periphery with the periphery of the grinder and slidably mounted so as to be movable towards the axis of the grinder, a limiting member abutting against a fixed member at one end and against the support of the follower at the other end, movement of the grinder being governed by movement of an intermediate point of the limiting member.

10. In an abrading machine the combination of a grinding wheel, a circular follower in the same plane and in tangential contact with the grinding wheel at its periphery, each of the rotary members being slidably mounted, and a controlling member, the movement of one end of which is limited by a fixed member, the movement of the other end being limited by movement of the follower, and the movement of the grinder being limited by movement of an intermediate portion of the controlling member, whereby the grinder is constantly permitted to move towards the stock a distance equal to the radial reduction of the grinder.

11. A grinding mechanism comprising a rotatable grinding wheel mounted on a movable support permitting the grinding wheel to move toward the stock to be ground, a follower the periphery of which constantly bears tangentially upon the periphery of said grinding wheel, said follower being mounted on a movable support permitting the axis of said follower to move toward the axis of said grinding wheel, and a flexible member connecting the grinding wheel support and the follower support with each other and with a fixed member whereby the movement of the grinding wheel support toward the stock is constantly limited to a distance equal to the radial reduction of the grinding wheel by wear.

12. A grinding mechanism comprising a rotatable grinding wheel mounted on a movable support permitting the grinding wheel to move toward the stock to be ground, a follower the periphery of which constantly bears tangentially upon the periphery of said grinding wheel, said follower being mounted on a movable support permitting the axis of said follower to move toward the axis of said grinding wheel, means continuously acting to move said grinding wheel support toward the stock to be ground and

the axis of said follower toward the axis of said grinding wheel and a flexible member attached at one end to the follower support and at the other end to a fixed member and carrying the grinding wheel support at an intermediate portion, whereby the movement of the grinding wheel support toward the stock is constantly limited to a distance equal to the radial reduction 10 of the grinding wheel by wear.

13. In an abrading machine, the combination of a circular grinder, having a carriage mounted to be slidable to and from the work being ground, a circular rotary follower adapted to contact tangentially with the grinder and mounted in a carriage slidable with respect to the carriage of the grinder so that the follower is free to move in the line of centers of the two rotary members, a cable attached at one end to a fixed member and at the other end to the carriage of the follower, the carriage of the grinder being suspended from an intermediate point in the cable, whereby the grinder is constantly limited in its forward movement to a travel equal to and coincident with travel of the follower towards the axis of the grinder.

14. A grinding mechanism comprising a circular abrading member constantly urged toward the stock being ground, a circular follower member positioned in the plane of the abrading member and constantly urged into peripheral contact therewith, and means limiting movement of the abrading member toward the stock to an amount coextensive with movement of the follower toward the axis of the abrading member.

15. In a grinding machine, the combination of a rotatable grinding wheel mounted on a movable support permitting the grinding wheel to move toward the stock to be ground, and means whereby the movement of the grinding wheel toward the stock to be ground is constantly limited to a distance equal to the radial reduction of said grinding wheel by wear, said means including as essential elements a rotary follower on a movable support, the periphery of the follower constantly bearing upon the grinding face of the grinding wheel, and positive connections between the supports of the grinding wheel and the follower.

16. A grinding mechanism comprising a rotatable grinding wheel mounted on a movable support permitting the grinding wheel to move toward the stock to be ground, a rotary follower the periphery of which constantly bears upon the periphery of said grinding wheel, said follower being mounted on a movable support permitting the axis of the follower to move toward the axis of said grinding wheel, the grinding wheel being constantly urged toward the stock to be ground and the follower toward the axis of the grinding wheel, and means constantly limiting the movement of the grinding wheel support toward the stock to a distance equal to the radial reduction of the grinding wheel by wear, said limiting means being controlled in operation by the movement of the follower toward the axis of the grinding wheel.

In testimony whereof, I sign my name.

ALBERT M. FULLER.
